Primary Examiner — Paula Allen Greene(74) *Attorney, Agent, or Firm* — Karish & Bjorgum, PC(57) **CLAIM**

The ornamental design for a headphones for VR headsets, as shown and described.

DESCRIPTION

FIG. 1 is front perspective view of an embodiment of left and right headphones for VR headsets of the invention with an optional microphone attached to the right headphone.

FIG. 2 is a back perspective view of the headphones for VR headsets of FIG. 1.

FIG. 3 is another front perspective view of the headphones for VR headsets of FIG. 1.

FIG. 4 is front view of a left headphone for VR headsets of FIG. 1.

FIG. 5 is front view of a right headphone for VR headsets of FIG. 1.

FIG. 6 is a top view of the headphones for VR headsets of FIG. 1.

FIG. 7 is a bottom view of the headphones for VR headsets of FIG. 1; and,

FIG. 8 is a front perspective view of the headphones for VR headsets of FIG. 1 with the optional microphone removed from the left headphone.

The broken lines shown represent unclaimed subject matter and form no part of the claimed design.

1 Claim, 6 Drawing Sheets(56)
